(57) **CLAIM**

The ornamental design for a multi-pole power connector system, as shown and described.

DESCRIPTION

FIG. 1 is a front view of a multi-pole power connector system showing our new design;

FIG. 2 is a back view thereof;

FIG. 3 is a right side view thereof;

FIG. 4 is a left side view thereof;

FIG. 5 is a top view thereof;

FIG. 6 is a bottom view thereof;

FIG. 7 is a top front perspective view thereof; and,

FIG. 8 is a top back perspective view thereof.

The broken line portion of the figure drawings is included to show unclaimed subject matter only and forms no part of the claimed design.

1 Claim, 8 Drawing Sheets

FIG. 1

FIG. 2

FIG. 4
